UNITED STATES PATENT OFFICE.

ROWLAND G. HOWARD, OF JACKSON, TENNESSEE.

ANCHORING DEVICE.

1,157,781.

Specification of Letters Patent.

Patented Oct. 26, 1915.

Application filed February 1, 1915. Serial No. 5,503.

To all whom it may concern:

Be it known that I, ROWLAND G. HOWARD, citizen of the United States, residing at Jackson, in the county of Madison and State 5 of Tennessee, have invented certain new and useful Improvements in Anchoring Devices, of which the following is a specification, reference being had to the accompanying drawings.

10 My invention relates to anchoring devices and particularly to devices of this character wherein a post is used to resist strain.

15 The primary object of my invention is the provision of a very simple and easily applied anchoring device including a post so constructed that it will not need to be buried in the ground and so formed that it may initially be disposed in an inclined position and brought to a vertical position under 20 strain.

Other objects will appear in the course of the following description.

My invention is illustrated in the accompanying drawings wherein:—

25 Figure 1 is a perspective view of my anchoring device. Fig. 2 is a section on the line 2—2 of Fig. 1. Fig. 3 is a view showing one of the anchoring pegs disposed in operative position.

30 As illustrated in the accompanying drawings my improved anchoring device comprises a base 1 having any suitable area and adapted to be placed upon the ground and to this base is hinged a post 2 by means of a hinge 3. The post 2 is provided with a plurality of vertically spaced perforations 4 designed to receive a bolt or pin 5 that extends through the arms 6 of a clip, this clip being U-shaped in form and adapted to be 35 connected to a chain 6^a or like flexible connection whereby strain may be applied upon the post.

40 The strain applied upon the post is resisted by means of the oppositely disposed chains 7 and 8. There are two pairs of these chains 7 and 8, the chains of each pair being disposed in divergent relation. Each pair of chains is connected at one end to a clip 9, U-shaped in form and adapted to embrace the post 2 and to be held in engagement with the post by means of a bolt 10 or pin. The outer end of each of the chains 7 and 8 is connected to an anchoring pin 11, this pin having an arm 12 extending out at 45 an obtuse angle to the axis of the pin, the extremity of the arm being hook-shaped as

50 at 13 for engagement with the corresponding chain. It is to be particularly noted that the anchoring chains 7 and 8 which are disposed in the direction of pull are connected by the corresponding clip 9 to the lower end of the post, while the anchoring chains 7 and 8 which extend opposite to the direction of strain are disposed above the connection of the first-named pair of anchoring chains. As a consequence, the post has a double fulcrum. When it is drawn upward by the straining chain 6^a from an inclined position away from the direction of strain to a vertical position, the lower 55 end of the post will tend to move rearward thus tightening the first-named pair of anchoring chains, while the post above the lower end will move forward thus tightening the second pair of anchoring chains. It 60 will be noted that these arms 12 on the several pins 11 are so disposed that when the pins are driven or forced downward at an inclination away from the direction of strain, the arms will lie flat upon the ground 65 and thus actually resist any tendency of the pin or peg moving into a vertical position 70 under strain.

75 The particular form of anchor which I have now described is adapted for many 80 purposes particularly because of the fact that the post does not have to be driven into the ground in order to secure a relatively solid bearing for the chain 6. It is particularly adapted for stretching wire fence and 85 also may be used in railroad practice where an anchor is required for clearing away railroad wrecks or for the application of tackle.

90 In the operation of my invention the anchors on the side toward the direction of pull are first set and as the post is on a hinge the post can be inclined away from the point of pull and the outer pair of anchoring pegs forced into the ground preferably as 95 indicated by dotted lines in Fig. 3. By thus 100 initially setting the anchors on the opposite side from the direction of pull then the movement of the post to a vertical position under strain will take up slack in the chains and set the anchoring pegs further into the 105 ground in the manner indicated in Fig. 3. When the post reaches a vertical position 110 the anchors will be firmly set and all of the slack will be taken out of the two pairs of chains thus avoiding the post leaning in the direction of the pull on the straining chain 6^a after a hard strain is placed upon the post.

It will be obvious that the two pairs of chains 7 and 8 are at first moderately slack but that upon the movement of the post from an inclined position to a vertical position under the action of strain the anchoring chains will be tightened up and if they have been set properly in the first instance the post will be firmly held against any movement. The strain on the post is of course resisted by both sets of anchoring pegs and inasmuch as these pegs may be set in any position and the post rotated or shifted to any desired position, it is obvious that my anchoring device is readily adaptable to all conditions and may be very readily set up.

It is of course obvious that the post may be made of any size and of any weight according to the work expected of it and that it may have any desired form in cross section.

Having described my invention what I claim is:

1. An anchoring device of the character described, comprising a base plate, a post hinged to said base plate for movement in a vertical plane, said post being formed with a vertical series of perforations, a straining connection adjustably and detachably engaged with the post, a clip engaged with the lower portion of the post and disposed on the hinged side thereof, divergent anchoring connections extending upon the said clip, ground engaging members attached to the ends of said anchoring connections, a clip attached to the post below the first-named clip and disposed oppositely to the hinge, outwardly divergent anchoring connections extending from the clip, and ground engaging members attached to the ends of said anchoring connections.
2. An anchoring device, comprising a base plate, a post hinged thereto for movement in a vertical plane, a strain applying member connected to the post, anchoring connections extending from the lower portion of the post and opposite to the hinged connection of the post to the base, anchoring connections attached to the post above the last-named anchoring connection and extending in an op-

posite direction to the first named anchoring connection, and ground engaging members connected to said anchoring connections, said ground engaging members comprising a pointed peg adapted to be driven into the ground and an arm extending from the peg at an obtuse angle thereto, said arm being formed at its extremity to engage with the corresponding anchoring connection.

3. An anchoring device of the character described comprising a base plate adapted to be placed upon the ground, a post mounted upon the base plate, a straining member detachably and adjustably connected to the post, a clip detachably connected to the post, anchoring connections extending from the clip, ground engaging members attached to the anchoring connections, a clip detachably connected to the post below the first-named clip and extending in an opposite direction thereto, anchoring connections extending from the last-named clip, and ground engaging members attached to the ends of said connections.

4. The combination with an anchoring post, of an anchoring connection extending in one direction from the lower end of the post and flexibly connected thereto and embodying divergent members, an anchoring connection flexibly connected to the post above the first-named connection and extending opposite to the first named connection and embodying divergent members, a strain applying member connected to the upper end of the post and extending in the direction of the first named anchoring connection, and anchors attached to the ends of the anchoring connection, each anchor comprising a pin and an arm extending from the pin at an obtuse angle thereto and acting to limit the penetration of the pin in the ground when strain is applied thereto.

In testimony whereof I hereunto affix my signature in the presence of two witnesses.

ROWLAND G. HOWARD.
